CLAIM

The ornamental design for a suction and irrigation tip for laparoscopic surgery, as shown and described.

DESCRIPTION

FIG. 1 is a perspective view of the suction and irrigation tip for laparoscopic surgery.

FIG 2 is an alternate perspective view of the suction and irrigation tip for laparoscopic surgery in greater detail.

FIG 3 is a rear elevational view of suction and irrigation tip for laparoscopic surgery.

FIG. 4 is a front elevational view thereof.

FIG. 5 is a top plan view thereof.

FIG. 6 is a bottom plan view thereof.

FIG. 7 is a right side elevational view thereof; and,

FIG. 8 is a left side elevational view thereof.
